(57) **CLAIM**

(51) LOC (7) Cl. **13-03**

The ornamental design for an electrical connector, as shown

(52) U.S. Cl. **D13/147; 439/607**

and described.

(58) Field of Search D30/146-47, 120,

DESCRIPTION

D30/133; 439/352, 359, 362, 610, 607,

FIG. 1 is a front, top, and right side perspective view of an electrical connector;

609

FIG. 2 is a rear, bottom, and right side perspective view thereof;

(56) **References Cited**

FIG. 3 is a front elevational view thereof;

U.S. PATENT DOCUMENTS

FIG. 4 is a top plan view thereof;

5,580,283 A 12/1996 O'Sullivan et al.

FIG. 5 is a bottom plan view thereof;

D420,979 S 2/2000 Chang

FIG. 6 is a rear elevational view thereof;

6,193,555 B1 * 2/2001 Chang 439/608

FIG. 7 is a right side elevational view thereof; and,

6,299,482 B1 * 10/2001 Huang 439/607

FIG. 8 is a sectional view taken along a line 8—8 of FIG. 3. A left side elevational view of the electrical connector is omitted because it is presented symmetrical to the right side elevational view of FIG. 7.
